UNITED STATES PATENT OFFICE.

DAVID C. RYDER, OF CATSKILL, NEW YORK, ASSIGNOR TO JOHN N. BRIGGS,
OF COEYMAN'S, NEW YORK.

STOP-MOTION.

SPECIFICATION forming part of Letters Patent No. 557,612, dated April 7, 1896.

Application filed May 12, 1894. Serial No. 511,002. (No model.)

To all whom it may concern:

Be it known that I, DAVID C. RYDER, of Catskill, in the county of Greene and State of New York, have invented a new and useful 5 Stop-Motion for Preventing Machinery being Rotated in a Wrong Direction, of which the following is a specification.

In many classes of machines, but especially in machines used for elevating cakes of ice, 10 much damage is done by the reversal of the direction of the moving parts of the machine, which reversal may be occasioned by the slipping or breaking of driving-belts, overloading the machine beyond its capacity, and by many 15 other causes, or the machine may be carelessly started in a direction contrary to the one it is designed to be run; and the object of my invention is to prevent a machine from being rotated in a wrong direction. This object I 20 attain by the mechanism illustrated in the accompanying drawings, which are herein referred to and form part of this specification, and in which—

Figure 1 is a side elevation of my invention 25 as applied to an ice-elevator, only a portion of the latter being shown. Fig. 2 is a detached plan view of the end of the detent-arm. Fig. 3 is an enlarged longitudinal section of the bracket secured to the end of the detent- 30 arm, the spur-wheel on which the stop-motion operates being broken out to expose underlying parts. Fig. 4 is a horizontal section of Fig. 3 at the irregular line X X, showing the upper side of the head of the bracket. Fig. 35 5 is a transverse section of Fig. 4 at the line Y Y. Figs. 6 and 7 are horizontal sections of the head of the bracket, showing modifications of the gripping mechanism.

As represented in the drawings, A is a de- 40 tent-arm having one end pivotally secured to a side piece 1 of an ice-elevator.

B is a spur-wheel secured to a sprocket-wheel shaft 2, said sprocket-wheels, to prevent confusion, not being shown.

45 C is a pinion secured to a driving-shaft 3, and meshing into the spur-wheel B. Said driving-shaft is usually driven by a belt 4, (indicated by dotted lines in Fig. 1,) and D is a bracket secured to the free end of the de- 50 tent-arm A.

The free end of the detent-arm A should be

held by adjustable guys 5 or other suitable means from bearing on the teeth of the spur-wheel B, and thus an unnecessary wear of the parts will be avoided. When the guys 5 55 are used, they can be attached to some adjacent overhead parts of the structure or housing of the machine, and said guys should be arranged so as to effect an adjustment of the outer extremity of the detent-arm A in re- 60 spect to the center of the wheel B, and to prevent a swaying movement of said arm. Said guys can be attached to a rib 6 of the bracket D or to any suitable part or attachment of the detent-arm. The latter is arranged in rela- 65 tion to the spur-wheel B in such manner that when said wheel is revolving in the direction indicated by the arrow in Fig. 1, its fixed end will be in a position to resist a pulling strain, if such a strain should be exerted on said arm. 70 The arm A may be made of wood or any suitable material with the metallic bracket D secured thereto, substantially as shown in the drawings; but when said arm is made of metal, which in some cases is preferable, the 75 arm and bracket can be integral.

The bracket D has parallel side flanges 7, which are spaced apart sufficiently to allow the rim of the wheel B to pass freely between them. In the forms of said bracket shown 80 in Figs. 4 and 6 each side flange is provided with a chamber 8 whose inner face has two inclined planes 9 which, in the opposite flanges, incline toward each other as they approach the fixed end of the arm A. In the 85 form shown in Fig. 5 the top and bottom faces of each chamber are each provided with a lip 10, which forms a retainer for keeping spherical rollers 11 in each compartment of the chamber, said compartments correspond- 90 ing in length to the inclined plane that forms the inner face of the compartment. Each lip is provided with a cut-out 12 that allows a roller 11 to be inserted in the deeper end of the corresponding compartment. The in- 95 clined planes 9 are arranged in such manner that, with the rollers in the deepest part of the compartments and the wheel B being rotated in the proper direction, the rim of said wheel will pass between said rollers 100 without frictional contact therewith; but im- mediately on the reversal of the direction of

movement of said wheel the rollers 11 will move toward the narrower part of the compartments and be forced against the opposite edges of the rim of the wheel B and grip 5 said rim with such tenacity that said wheel will be held immovably thereby until a reversal of the direction of movement of said wheel returns said rollers to the deeper part 10 of the compartments, whereupon the wheel B will be left free to revolve in the proper direction. For the purpose of maintaining the bracket D in a proper position in respect to the rim of the wheel B, adjustable bearing-pins 13 are inserted in the side flanges of 15 the bracket D to bear against the sides of the rim of said wheel. Said bearing-pins are preferably made of wood, and they may be either screwed or driven into holes formed for that purpose in the side flanges 7, and as the inner ends of said bearing-pins become worn away the bearing-pins can be readjusted to bear against the edges of the rim of the wheel.

Preferably the end of the bracket of each 20 form herein shown and described is provided with lugs 14, to which a safety-check E can be attached. Said safety-check is designed to operate in case when from any cause the rollers 11, or other clamping mechanisms herein 25 shown and described, may fail to prevent the wheel B from revolving in the wrong direction; and it consists of arms 15, which extend from the end of the bracket, and tilting levers 16, which are loosely fitted to oscillate 30 on an arbor 17 attached to said arms. The posterior arms 18 of said levers are arranged to bear upon the teeth of the wheel B, and preferably they are of sufficient length to bear simultaneously upon two of said teeth, 35 so as to prevent the opposite ends of said levers from being raised above their proper position. The anterior arms 19 of said levers are connected by a cross-bar 20 whose lower part inclines outwardly, so as to allow the 40 teeth of the wheel B, when the latter is revolving in the proper direction, to raise the anterior end of the levers 16, and when said wheel begins to revolve in the contrary direction the cross-bar 20 will engage with the 45 advancing side of a tooth of said wheel and be carried down to the bottom of the space between two adjacent teeth and thereby positively prevent the wheel from revolving farther in that direction. The arms 19 are bent 50 to form an opening 21 which, when the levers 16 are tilted to carry the cross-bar 20 into a space between two of the teeth, will allow a tooth of the wheel to enter therein, as indicated by dotted lines in Fig. 3.

55 The pivot on which the levers 16 are arranged to oscillate is located in relation to a shoulder 22 on each of said levers, so that the latter will acquire a slight oscillatory motion when said shoulders are about midway between two adjacent teeth of the wheel B, and thereby the cross-bar 20 will be carried into a position where it will take against a tooth

of the wheel B in case the latter is revolving in the wrong direction, and said wheel will be positively stopped in the manner above 70 described. On resuming the motion of said wheel in the proper direction the succeeding tooth of the wheel B will take against the inner side of the cross-bar 20, and, by the angularity of the latter, the levers 16 will be restored to their normal position, so that the wheel B can be revolved in the proper direction. 75

In the modification shown in Fig. 6 the bracket D is provided with chambers 23, which 80 are substantially the same as those previously described in respect to Fig. 5; but instead of the spherical rollers shown in the last-named figure wedge-shaped blocks 24 are inserted in said chambers to bear against the faces of the 85 inclined planes 25, with the adjacent faces of said blocks slightly touching the edges of the rim of the wheel B without interfering with the latter when revolving in the proper direction, but when said wheel begins to revolve in the wrong direction the blocks 24 90 will be automatically moved toward the shallower part of said chambers until they immovably clamp the wheel B, and in this manner they effect the result described in respect 95 to the said spherical rollers.

In the modification shown in Fig. 7 the bracket D² is provided with chambers 26, in which cams or disks 27 are pivoted eccentrically and arranged in such manner that, when 100 the wheel B begins to revolve in the wrong direction, the fuller part of said disks will be carried to bear with exceeding pressure against the edges of the wheel-rim, and thereby the motion of said wheel will be stopped. 105 Each disk 27 has its periphery provided with an angular projection 28 to prevent its being rotated too far in either direction, said projection taking against the rim of the wheel B when the disk is rotated in one direction and 110 against the back of a chamber 26 when rotated in the opposite direction, but in either case the rotations of the disk will be stopped by said projection.

What I claim as my invention, and desire 115 to secure by Letters Patent, is—

1. The combination of a revoluble wheel, B, a detent-arm, A, having one of its ends pivoted to the housing of said wheel and its opposite end supported by adjustable guys, 5, 120 and a head, D, secured to the adjustable end of the detent-arm and provided with side flanges, 7, which pass down loosely at each side of the rim of said wheel; each of said flanges being provided with a chamber, 8, and gripping mechanism therein—substantially as shown and described—adapted to grip the rim of said wheel when rotating in the wrong direction, as herein specified. 125

2. The combination of a revoluble wheel, B, 130 a detent-arm, A, having one end pivoted to the housing for said wheel and its opposite end supported by adjustable guys, 5, and provided with a head, D, having side flanges, 7,

provided with chambers, 8, whose inner face is formed by inclined planes, 9, and whose outer sides are open adjacently to the rim of said wheel, and rollers, 11, loosely placed in said chambers with a segmental portion of the rollers projecting from said chambers; said rollers being arranged to automatically grip the opposite edges of the wheel-rim when the latter is rotated in a wrong direction, as herein specified.

3. The combination of a detent-arm, A, provided with a head, D, having parallel pendent

side flanges, 7, gripping means in said head, and bearing-pins, 13, inserted in said flanges and adjustable from and toward each other; 15 said bearing-pins being arranged to bear against opposite sides of the rim of the wheel B to retain the head D in position in respect to the rim of said wheel, as and for the purpose specified.

DAVID C. RYDER.
